(57) CLAIM

The ornamental design of a decorative baluster, as shown
and described.

DESCRIPTION

FIG. 1 is a side elevational view of a decorative baluster in
accordance with my original design, the opposite side being
identical in appearance;

FIG. 2 is a side elevational view of a first variant of the
design for the decorative baluster shown in FIG. 1, the
opposite side being identical in appearance;

FIG. 3 is a second variant for the design for the decorative
baluster shown in FIG. 1;

FIG. 4 is a top plan view of the decorative baluster shown
in FIGS. 1-3; and,

FIG. 5 is a bottom plan view of the decorative baluster
shown in FIGS. 1-3.
